W. A. BUSIEK

RANGE

Filed Oct. 16, 1922

WILLIAM A. BUSIEN.
by Arthur C. Eckert, attorney.

UNITED STATES PATENT OFFICE.

WILLIAM A. BUSIEK, OF BELLEVILLE, ILLINOIS.

RANGE.

Application filed October 16, 1922. Serial No. 594,770.

To all whom it may concern:

Be it known that WILLIAM A. BUSIEK, a citizen of the United States of America, residing at 625 East C Street, Belleville, in the county of St. Clair and State of Illinois, has invented certain new and useful Improvements in Ranges, of which the following is a specification.

The object of my invention is to make a gas range which will when in operation produce an equality in temperature in all portions of the oven. A further object is to provide a range with adequate circulation and one that utilizes a double burner. A further object is to make a range that is composed of standard parts, can easily be assembled and lends itself readily in multiple production. A still further object is to produce a range in which the burners are easily lighted and in which a positive circulation of heated air results.

With these and other objects in view my invention has relation to certain novel features of construction and arrangement of parts as will be hereinafter more fully described, pointed out in the claims and illustrated in the drawings, in which—

Fig. 1 is a transverse sectional elevation.

Fig. 2 is a longitudinal sectional elevation.

Fig. 3 is a sectional plan view along the line of 3—3 of Fig. 2.

Fig. 4 is a sectional plan view along the line 4—4 of Fig. 2.

Numeral 5 designates the range generally having the top 6, the rear wall 7 with the legs 8 formed integral therewith and numeral 9 designates the front wall having the legs 10 formed integral therewith. Numeral 11 designates one of the side walls and numeral 12 the other side wall. The range thus far described is made of standard sheet metal construction. Numeral 13 designates one of the oven walls which is secured in spaced relationship to the side wall 11 and which does not extend to the top 6 and which is secured to the rear oven wall 14 at 14' and the front wall at 15 by normal construction. Numeral 16 designates another oven wall of the same dimensions and shape as the oven wall 13 and similarly secured to the rear oven wall 14 and 16'. The rear oven wall 14 is secured to the side walls 11 and 12 by the conventional construction and has the flue opening 17 formed therein and the holes 18. To the oven walls 13 and 16 is secured the oven base 19 which extends

to the front wall 9 and the rear oven wall 14. Numeral 20 designates the range floor on which are secured the stands 21 beneath the oven base 19. In eyes formed in the stands 21 are secured the gas burners 22 and 23. The burners 22 and 23 are positioned as best shown in Figs. 1 and 2 and held in that position by the stands 21. The ends of the burners 22 and 23 extend through the front wall 9 of the range by means of the projections 24 and 25. A source of fuel is connected to the projections 24 and 25.

Supported on the stands 21 is positioned the baffle plate 26 which extends from the front of the oven rearwardly on an inclined plane upwardly, but not to the rear oven wall 14. Formed integrally laterally with the baffle plate 26 are the baffle extensions 27 which protrude over the stands 21, the lateral edges of which are above the plane of the burners 22 and 23 and substantially parallel therewith. In the range floor are positioned the combustion openings 28. The conventional flue 29 is provided to establish communication between the rear wall and the rear oven wall 14. It will be seen that by reason of the rear wall 7 and the rear oven wall 14 that a flue is established behind the oven and that by reason of the side walls 11 and the oven wall 13 a flue is established and by reason of the side wall 12 and the oven wall 16 a flue is established.

The circulation of heat from the burners 22 and 23 is shown by the arrows in Figs. 1 and 2. The heat emanating from the burners and baffled underneath the baffle plate 26 passes beneath the baffle plate 26 rearwardly through holes in the rear oven wall 14 into the flue formed between the rear wall 7 and the rear oven wall 14 and out the flue 29. The heated air from the burners 22 which is deflected by the baffle extensions 27 laterally passes up the flues formed between the oven walls 13, the side walls 11 on one side and the oven wall 16 and the side wall 12 on to the other side over the oven walls 13 and 16 at their top into the oven and to the flue opening 17 into the flue formed between the rear wall 7 and the rear oven wall 14. The baffle extensions 27 perform the dual function of deflecting a portion of the heat from the burners 22 under the baffle plate 26 and the remainder of the heated air into the flues previously described. It is desirous in lighting the burners that a portion of the flue be deflected as indicated. The inclina-

tion of the baffle plate 26 takes care of the increased volume of the heated air as it passes rearwardly.

What I claim and mean to secure by Letters Patent is—

1. In a range, an oven, said oven positioned in said range so as to form flues in said range, a source of heat positioned beneath said oven, baffle extensions positioned 10 on said source of heat so as to deflect heated air from the source of heat into the flues formed by the oven and the range, and separately underneath said baffle extensions underneath said oven.
15. 2. In a range having an oven positioned therein, a baffle plate positioned under said oven, a source of heat positioned under said baffle plate, said baffle plate having baffle extensions formed integrally laterally there- 20 with so as to form deflectors for the heated air emanating from said source of heat so
- 25 as to divide said heated air into separate systems of circulation, one of which passes beneath said baffle plate beneath the oven and the other passes through flues formed by said range and said oven walls.
- 30 3. In a range having an oven positioned therein, a source of heat and a baffle plate both positioned under said oven, the source of heat positioned on the oven floor and the baffle plate supported by the source of heat, 35 said baffle plate having baffle extensions formed integrally and laterally therewith so as to form deflectors for the heated air emanating from said source of heat so as to divide said heated air into separate systems of circulation, one of which passes beneath said baffle plate beneath the oven and the other passes through flues formed by said range and said oven walls.

In testimony whereof I affix my signature.

WILLIAM A. BUSIEK.
